UNITED STATES PATENT OFFICE.

HANNAH E. ROGERS, OF PORTLAND, MAINE.

ABDOMINAL SUPPORTER.

SPECIFICATION forming part of Letters Patent No. 433,370, dated July 29, 1890.

Application filed April 14, 1890. Serial No. 347,798. (No model.)

To all whom it may concern:

Be it known that I, HANNAH E. ROGERS, a citizen of the United States, residing at Portland, in the county of Cumberland and State of Maine, have invented certain new and useful Improvements in Abdominal Supporters; and I do hereby declare the following to be a full, clear, and exact description of the invention, such as will enable others skilled in the art to which it appertains to make and use the same.

The invention relates to improvements in abdominal supporters, the object being to provide a simple device that the wearer can put in place without the aid of a second person, and which will relieve the oppression that is liable to occur from gravitation.

The device is more particularly adapted to persons who, from want of sufficient exercise or other cause, develop a tendency toward corpulency.

The invention consists, mainly, in the peculiar structure, the composite body portion or strap-work that surrounds the body of the wearer, the combination of the parts, and, further, in the means by which said body portion is retained in place, all of which is hereinafter fully described, illustrated in the drawings, and pointed out in the appended claims.

In the accompanying drawings, in which similar letters of reference indicate similar parts, Figure 1 represents a perspective view of a device embodying the invention. Fig. 2 represents a front view of the device applied to the body. Figs. 3 and 4 respectively represent rear and side views thereof similarly applied.

Referring to the drawings by letter, A A are similar side bands having the vertical front and rear portions $a a'$, respectively. The said bands are of inelastic material, and the rear portions a' have horizontal extensions a^2 at their lower ends.

B B are horizontal elastic bands, which are below and parallel with the inelastic parts of the bands A, and are adapted to rest against the side of the wearer and connect at front and rear the vertical portions $a a'$ of the bands A on each side, which preferably have their ends secured firmly by stitching or otherwise to said portions.

C C are horizontal elastic bands connecting the rear portions $a' a'$ of the two bands A. These bands have each, preferably, one end stitched to the rear part a' of one band A, 55 and the opposite end connected to the opposite part a' by a buckle or equivalent means of longitudinal adjustment, as shown.

D is a lacing-cord, which is passed through eyelets $d d$ in the vertical portions $a a$ of the side bands A, so that when the device is in place it may be laced up from the front, the diameter being adjusted by the rear elastic straps.

Stocking-supporters E E may be attached 65 to the lower edge of the abdominal supporter at suitable points, and will help keep the supporter in place.

The ends of the horizontal extension a^2 of the rear vertical portions a' of the side bands 70 are connected by a lacing-strap F, engaging in eyelets $f f$ in said ends.

By means of the lacing at front and rear and the buckles, as has been described, the same supporter can be readily adapted to persons of different sizes, which is of great advantage in the sale of the goods; also, in general terms, it is only necessary in making these devices for the market to have one form or size for the inelastic part. 75

It will be noted that the vertical portions a of the inelastic part A are adapted to fit snugly and smoothly against the abdomen almost directly in front, while just at the rear of the hips on the side the vertical portions a' of 85 said part A give stay and form to the entire structure. Thus these vertical portions are placed at exactly the best points for effective use and precisely where they cannot interfere with the motion of the body, while at the 90 back and opposite to said portions the elastic strap C, coming above the inelastic horizontal extension a^2 , that rests against the body, serves, with the aid of the elastic side straps B, to secure closeness of fit, permit entire freedom in the motion of the body, and at the same time prevents any binding or closeness. 95

The described supporter has this peculiar advantage of being adjustable by the wearer without the aid of an assistant, even when 100 want of exercise or other causes have produced undue corpulency, as the lacing is done

- from the front of the supporter, thus having a great advantage over the ordinary supporter opening in the back. In addition to this, the device is so open that it cannot heat the body 5 of the wearer, while at the same time it remains well in place and supports all the parts of the abdomen in an easy manner, so that the wearer is practically unconscious of any such appliance. The peculiar structure has also 10 this further advantage, that in any motion of stooping or bending there is so much flexibility at the point where any strain comes that the wearer practically suffers no inconvenience from the device.
- 15 I am aware that heretofore devices of this general character and description have been made and used, and I do not assert, therefore, that it is broadly new to use bands, elastics, and lacing for this purpose.
- 20 Having described my invention, I claim—
1. An abdominal supporter comprising the opposite similar side bands of inelastic material, their vertical front and rear portions con-

nected by straps or cords at their ends in front and at the back, and provided with elastic bands which connect the said front and rear portions on the same side, and with the elastic bands adjustably connecting the vertical rear portions of the two side bands, substantially as specified. 25

2. The herein - described abdominal supporter having the vertical inelastic front portions a connected by elastic and inelastic side bands with the rear vertical portions a' and the elastic bands C and inelastic part a^2 below, the several parts adapted, by means of the lacing D and F , to be fitted to any size of wearer and secured in position, substantially as set forth. 30

In testimony whereof I affix my signature 40 in presence of two witnesses.

HANNAH E. ROGERS.
